TRAILER WASTE OUTLET COUPLING WITH OPPOSITELY THREADED FEMALE MEMBER

Claude E. Hand, 1402 3rd St., La Grande, Oreg. 97850

Filed Nov. 11, 1971, Ser. No. 198,036

Term of patent 14 years

Int. Cl. D23—01

U.S. Cl. D23—43

FIG. 1

FIG. 2

FIG. 3

FIG. 1 is a side elevational view of a trailer waste outlet coupling with oppositely threaded female member, showing my new design, and

FIG. 2 is a left end elevational view thereof, and
FIG. 3 is a right end elevational view thereof.

I claim:

The ornamental design for a trailer waste outlet coupling with oppositely threaded female member, as shown.
